(57) **CLAIM**

The ornamental design for a chandelier, as shown and described.

DESCRIPTION

FIG. 1 is a front perspective view of a chandelier; FIG. 2 is a front elevational view of FIG. 1; FIG. 3 is a top plan view of FIG. 1; and, FIG. 4 is a perspective bottom view of FIG. 1. The broken lines shown on the drawings depict portions of the chandelier that form no part of the claimed design.
